United States Patent Office.

HENRY A. FOLLETT AND AMOS FOLLETT, OF SMITHFIELD, RHODE ISLAND.

Letters Patent No. 67,521, dated August 6, 1867.

IMPROVED BED-BOTTOM.

The Schedule referred to in these Letters Patent and making part of the same.

TO ALL WHOM IT MAY CONCERN:

Be it known that we, HENRY A. FOLLETT and AMOS FOLLETT, of Central Falls, (Smithfield,) in the county of Providence, and State of Rhode Island, have invented certain new and useful Improvements in Bed-Bottoms; and we do hereby declare that the following specification, taken in connection with the drawings making a part of the same, is a full, clear, and exact description thereof.

Figure 1 is a top view, and

Figure 2 is a side view of a bedstead with the improvement attached.

Figure 3 is a top view of the series of bottom spring-bar slats.

Figure 4 is a side view of the series of top slats or gridiron-slat frame resting upon the spring-bar slats and supporting the mattress.

Our invention consists in the use of two independent sets of slats, so arranged that each slat shall constitute a "spring-board," the slats of each set being disposed alternately with the slats of the other set; the spring ends of one set being at the head, and those of the other set at the foot of the bedstead; and also in combining with such spring-slats an ordinary slat-frame or other support for the bed mattress.

In the drawings, A represents a bedstead of well-known form and construction. The slats *e* and *e'*, fig. 2, which are to compose the bottom, instead of resting at their ends in notches cut in the foot and head-rails of the bedstead, are divided into two sets, and so spaced that the slats of the two sets, when arranged as presently to be described, will alternate with each other, and in the aggregate occupy, with the usual allowance for spaces, the distance between the side rails of the bedstead. The slats of each set are fitted at one end to enter mortises cut in the head and foot-rails *a* *b* at distances corresponding with the distances of the slats apart, but their other ends are without any support whatever from the frame of the bedstead. Midway, or thereabouts, between the head and foot-rails of the bedstead is placed a strong transverse rail, B, upon the top surface of which the slats of each set rest. Near the springing ends of the slats, and upon their top surfaces, is secured a block of wood, *c*, whose thickness should be greater than the probable length of the sine of the angle of deflection of the slats, due to the expected weight to be placed upon them. A transverse slat, *d*, is for convenience nailed to the blocks *c* of each set of slats respectively, and thus each set of slats is connected. They are thus to be arranged, so that the springing ends of one set shall be at the head, and those of the other at the foot of the bedstead. Resting upon the transverse slats *d* of this spring-bottom, so constructed, is laid a gridiron-slat frame, C, upon which the bed-mattress is to be placed.

It is quite evident from the foregoing description that the slats of each set constitute so many spring-boards which support the gridiron-frame C, the mattress, and the weight of the occupants of the bed. All the parts are readily removable, and whenever, from long use, the spring-boards have become bent and lose their elasticity both sets can, in a few moments of time, be turned over.

What we claim as our invention, and desire to secure by Letters Patent, is—

1. A bed-bottom composed of two sets of spring-bars *e* *e'* in alternation, one end of the bars of each set being held fast, and the other end left free to spring, and arranged so that one-half, or nearly so, of such bars will have their springing ends at the head, and the residue at the foot of the bedstead, all of such bars being combined with a transverse rail, B, or other suitable fixed support for the same, the improvement being substantially as herein described.

2. A bed-bottom, constructed and arranged as above described, in combination with a slat-frame, C, or other proper support for the mattress, substantially as described.

HENRY A. FOLLETT,
AMOS FOLLETT.
